WINDGUARD FOR AUTOMOBILES

Filed April 12, 1930

FIG. 1

FIG. 2

FIG. 3

FIG. 4

Inventor.
Robert C. Wall.

By Attorney.

UNITED STATES PATENT OFFICE

ROBERT C. WALL, OF PHILADELPHIA, PENNSYLVANIA

WINDGUARD FOR AUTOMOBILES

Application filed April 12, 1930. Serial No. 443,656.

The object of my invention is to provide an automobile having side glass wind deflectors hinged to the wind shield frame, with special means yieldingly connecting the 5 said deflectors with the side doors in such a manner that the deflectors swing with the respective doors, so that they are automatically moved out of the way of side door entrances whenever the doors are opened, and 10 swing into shielding position when the doors are closed.

More specifically, my invention embodies special improvements in the connecting means between the side wind deflectors and 15 the respective side doors, the same comprising flexible connecting devices adapted to be bent upon and over the upper side portions of the side doors whereby the same are steadied and all loose rattling avoided.

In the preferred form of my invention, 20 the axes of the hinges on the side door and of the side deflector are out of alignment and hence the side door and deflector shift their relative movement and the connection 25 between them is removed from the hinges to the free ends of both the side doors and deflectors, said connecting means comprising a yielding device which presses down upon the upper portion of the side door and holds the 30 side shield tightly down upon the upper rim thereof and in that manner steadies the deflector during the running of the machine.

My invention also comprehends certain 35 improvements in the connecting means, which together with the association of parts enumerated, are more fully described hereinafter and more particularly pointed out in the claims.

Referring to the drawings, Fig. 1 is a side 40 elevation of a motor car embodying my invention; Fig. 2 is a plan view of a portion of the same taken on line 3—3 of Fig. 2; Fig. 3 is a vertical sectional view of the 45 same; Fig. 4 is a side view of one form of

the flexible connecting device after being applied to the windguard.

The body 2 of the car is the open or phaeton type having low side doors 3, hinged at their forward ends as at 4, 4. As 50 improvements are the same on each side of the car, it will suffice to describe those at one side only.

Above the door 3 and of a width substantially that of the door is a glass windguard 55 7 having a surrounding metal frame 6 which is hinged at its forward portion to the side posts of the windshield 5 as indicated at 8, the hinge being preferably of the character known as a "piano" hinge. I however, do 60 not limit myself to any particular type of hinge. The axis of the hinge 8 is in general aligned position with the hinges 4, 4, of the side door 3, but more specifically the windshield post is slightly inclined backward and 65 the guard hinge 8 is likewise arranged on said incline. This causes the axis of the guard hinge 8 to lie at an angle to the axis of the door hinges 4, 4, and consequently necessitating the side windguards to swing 70 about said inclined hinges and cause the general plane of the guard to assume an increasing inclination as the door and guard swing in opening about their respective 75 hinges.

It will be further seen from Figs. 2 and 3 that the windguards flared downwardly at their rear ends and this causes the lower edge of the windguard to rise during the opening movement of the door and guard, and so 80 reverse cause the lower edge of the windguard to descend as the door and guard are being closed so that when fully closed, the guard has drawn the flexible connecting device 9 downward and with a downward pressure directly upon the upper surface of the door 3 as shown in Figs. 3 and 4. This operation provides a construction which holds the windguard firmly and at the same time provides a yielding union which prevents any 85 90

undue vibration or rattling of the windguard when the door is closed and the automobile in motion.

Referring more particularly to Fig. 4, it will be seen that the flexible connecting device 9 comprises an inner helical spring 13 surrounded with a rubber sheath 14 and with the spring connected to a flange head 10 provided with a shank 12 fitting into the coil spring, said head having an angular socket portion which is shaped to receive the lower frame 6 of the windguard. The other end of the flexible device 9 is connected to a bracket 15 having a socket portion into which the spring and rubber covering is received and also provided with a flange 17 at right angles to said socket portion for attachment to the inside of the door by means of a screw or bolt as shown at 18 in Fig. 3. The socket portion 15 is preferably provided with a coarse screw-like device 16 which extends through the socket portion and up into the coil spring, the interior of the latter constituting in effect an internal screwthread into which the screw-like device 16 enters for gripping and holding the flexible device firmly to the bracket. This device when unattached would preferably be straight in form but when attached to the windshield and door, it will assume a curved condition as more fully indicated in Fig. 3 and will at all times tend to hold the windguard in proper relation to the side door of the vehicle.

While I have shown in Fig. 4 the flexible connecting device as having a coil spring core, it will be understood that this coil spring may be omitted and the rubber casing made either solid or with very thick walls as indicated in Fig. 3. I prefer, however, that the connection between the bracket 15 and the head 10 shall be of a metallic nature to prevent actual severance at any time.

It will now be apparent that I have devised a novel and useful construction which embodies the feature of advantage enumerated as desirable, and while I have in the present instance shown and described the preferred embodiment thereof which has been found in practice to give satisfactory and reliable results, it is to be understood that I do not restrict myself to the details as the same are susceptible of modification in various particulars, without departing from the spirit or scope of the invention.

55. What I claim is:

1. The combination in an automobile of a side door thereof with a windguard hinged to the automobile in general alignment with the position of the hinge of the door and normally positioned above the door on an independent hinge having an axis at an angle to the axis of the door so that the windguard and door may be simultaneously swung into open and closed positions and a mechanical connection between the windguard and the

side door arranged at a distance from the hinge points thereof, said connection comprising a flexible link connected to the door on the inside and extending upwardly and over the upper part of the door to a point outside thereof and mechanically connected thereto to the lower part of the windguard so as to hold it spaced from the door, said link providing a universally flexible attachment between the door and windguard whereby they both may be opened and closed while connected. 70 75

2. The invention according to claim 1, wherein further, the flexible link connection between the door and the windshield is formed of a flexible body part positively connected at its opposite ends with the door and windguard, said flexible body part constituting a spring flexibly and yieldingly curved outwardly over the upper portion of the door 80 85 upon which it frictionally presses.

3. The invention according to claim 1, wherein further, the flexible link connection has its body part formed of a helically coiled spring having its lower part attached to the door and its upper part extended laterally over the door and connected to the lower part of the windguard, the spring action of the flexible link acting to bend over and frictionally bind upon the door by the action of the 90 95 windguard.

4. The invention according to claim 1, wherein further, the flexible link connection has its body part formed of a helically coiled spring surrounded by a rubber tube and having its lower part attached to the door and its upper part extended laterally over the upper edge of the door and rigidly connected to the lower part of the windguard whereby the latter in swinging about its own axis causes the flexible link to be pressed downward and bent over the upper edge of the door. 100 105

5. The invention according to claim 1, wherein further, the flexible link connection includes a heavy tubular rubber body extending vertically and laterally from the inside of the door and forcibly bent over the top of the same and attached to the bottom of the windguard. 110 115

6. The invention according to claim 1, wherein further, the hinge of the windguard is hinged in general alignment with the forward hinged end of the door but has its axis at an angle with the hinge axis of the door so that the windguard swings outward and upward while the hinged door swings horizontally in substantially the same plane and the flexible link connection between the said guard and door embodies elasticity sufficient to maintain an operative connection between the two parts to at all times control the windguard by the opening and closing of the hinged door. 120 125

7. The invention according to claim 1, 130

wherein further, the windguard is arranged outside of a vertical plane coincident with the plane of the door and wherein also the flexible link connection between the inside of the door 5 and the bottom of the windguard is pressed downward over and upon the upper edge of the door adjacent to its connection with the windguard to perform the dual function of moving the windguard when necessary and 10 also acting as a buffer to support the windguard against objectionable vibrations during the running of the automobile.

15 In testimony of which invention, I hereunto set my hand.

ROBERT C. WALL.
